UNITED STATES PATENT OFFICE.

WILLIAM H. PASCOE AND JOHN TATTER, OF CHICAGO, ILLINOIS.

ROTARY PUMP.

Application filed August 30, 1924. Serial No. 735,084.

The object of this invention is to produce a rotary pump of novel and improved construction which has a combined rotary and reciprocatory motion, which comprises a minimum number of parts so constructed that the pump may be cheaply manufactured, and which is durable and efficient in operation.

More specifically, it is an object of the invention to produce a pump in which a plunger is mounted in a rotor to rotate therewith and also to reciprocate transversely of the axis thereof, and to provide novel means for effecting a relative reciprocation of the plunger and rotor during their rotation together.

Another object is to produce a pump comprising two rotor parts turning on parallel but eccentric axes and each provided with diametrical guides arranged at right angles to each other; and a unitary plunger device having portions to reciprocate in both of said guides during rotation of said parts.

A further object is to produce a duplex pump in which both portions of the unitary plunger device mentioned in the last preceding object constitute plungers, each of which begins its stroke when the other plunger is half way through its stroke.

Another object is to produce a novel duplex plunger.

Another object is to provide a novel arrangement of passages for conducting fluid to and from the plunger chambers.

Additional and ancillary objects and advantages of the invention will be apparent from the following detailed description taken in connection with the accompanying drawings, in which—

Figure 1 is a side elevation of one form of pump embodying the features of our invention.

Fig. 2 is a horizontal section on an enlarged scale taken in the plane of line 2—2 of Fig. 1.

Fig. 3 is a perspective view showing the unitary duplex plunger.

Fig. 4 is an enlarged vertical section in the plane of line 4—4 of Fig. 2.

Fig. 5 is a similar section in the plane of line 5—5 of Fig. 2.

Figs. 6 and 7 are elevations of the abutting faces of the two casing sections respectively, the one in Fig. 7 being in inverted position.

We have shown in the drawings only one form or embodiment of our invention and

will herein describe that form in detail for the sake of illustration but it should be understood that this disclosure is given for the purpose of imparting an understanding of the principles of the invention and is not to be construed as an intention to limit ourselves to the particular embodiment shown and described. We propose to include all modifications and alternative constructions falling within the spirit and scope of the invention as defined in the appended claims.

Referring now to the drawings, the exemplary embodiment therein shown comprises a casing 10 composed of two similar half sections 10^a, 10^b, suitably secured together as by means of screws 11. The casing may be provided with a suitable base or support 12 which, in the present instance, is cast integral with the section 10^a.

The casing is preferably provided with nipples 13, 14 which form an inlet and an outlet and afford a convenient means for attachment of pipes. In the present instance both nipples are formed on the same casing section at opposite sides thereof, but the arrangement and location of said nipples may be varied to suit requirements.

Within the casing are two cylindrical bores 15, 16, the axes of which are parallel but eccentric or offset, said bores being formed in the respective casing sections and opening onto the abutting faces thereof. Two rotors 17, 18 fit in these bores with their adjacent side faces abutting against each other. One of these rotors, preferably 17, is fixed to and may be integral with a coaxial drive shaft 19 which extends through a bearing 20 in the casing and is provided with suitable driving means such as a pulley 21.

Each of the rotors 17, 18 has a transverse guide which are preferably in the form of slots 22, 23 in the abutting faces thereof, the slots extending diametrically across the rotors and having straight parallel sides. In the present instance the slots are rectangular or square in cross section. The two slots are disposed perpendicularly to each other and they receive a unitary duplex plunger element 24 comprising two slides 24^a, 24^b disposed perpendicularly to each other in symmetrical relation. These two plunger slides are rigidly fixed together and may be formed from an integral piece of metal. The length of the slides is less than the diameter of their respective rotors or the

length of the slots 22, 23 therein, so that said slots and slides act as cylinders and pistons providing chambers at opposite ends of the slides into and from which fluid is drawn and discharged in the operation of the pump.

The casing 10 is provided with a peculiar arrangement of passages and ports to supply fluid to and receive it from both piston and cylinder units. Leading from the inlet nipple 13 the casing section 10^a has a lower channel 25 running circumferentially nearly half way around the casing and communicating at one end with a port 26 which opens onto the side face of said section. Diametrically across from said port 26 another port 27 opens onto said casing face and communicates with an upper channel 28 which leads circumferentially around the casing and 20 communicates with the outlet nipple 14. These channels and ports are duplicated in the other casing section 10^b. There a port 29 opens onto the side face of said section and registers with the port 26 so as to receive fluid from the channel 25 and inlet 13, and this port 29 communicates with an upper channel 30 running circumferentially about half way around the casing section 10^b. Another port 31 leads from a lower circumferential channel 32 and opens onto the face of the casing section 10^b to register with the port 27 and deliver fluid into the channel 28 and outlet 14.

The ends of the exposed portions of the lower and upper channels 25, 28 or 32, 30 of either casing section are spaced apart a distance equal to the width of the associated plunger slide 24^a, or 24^b, so as to leave dead or cut-off portions 33 at diametrically opposite points in the periphery of the bore 15 or 16 to separate the inlet and outlet passages. These cut-off portions 33 in one casing-section are disposed in horizontal alignment with such portions in the other section.

In operation, when the drive shaft 19 is rotated, both of the rotors 17, 18, will be driven, the plunger element 24 communicating motion from the rotor 17 to the rotor 18. Due to the eccentricity of the rotors the two plunger slides 24^a, 24^b, will be caused to reciprocate in their guides or slots 22, 23, in the rotors. In Fig. 5 the slide 24^a is in its extreme right hand position at one end of a stroke. Assuming the rotors to be turning in a clockwise direction as indicated by the arrows, the opening 13 will be the inlet and the opening 14 will be the outlet. In the first half revolution from the position seen in Fig. 5 the right hand end of the slide 24^a will draw in fluid continuously from the inlet 13 and lower channel 25 and the fluid in the chamber at the left hand end of this slide will simultaneously be discharged into the upper channel 28 and outlet 14. At each

half revolution of the rotor the opposite ends of this slide act alternately to draw in and expel the fluid steadily, so that in each complete revolution there are two suction and two discharge impulses. The operation thus far refers only to the parts contained in the casing section 10^a seen in Fig. 5.

The action of the parts in the other casing section 10^b shown in Fig. 4 is the same as above described, but inasmuch as the two plunger slides 24^a, 24^b are perpendicular to each other, the suction and discharge stroke of each slide begins when the stroke of the other slide is half finished. Since both slides draw fluid from the common inlet and deliver it to the common outlet there will, in the pump as a whole, be four suction impulses and four discharge impulses at each complete revolution of the rotors.

It will be noted that the inlet channel for one section 10^a is at the bottom of the casing and for the other section 10^b is at the top, but these two channels overlap and are connected by ports 26, 29, at points adjacent to the cut-off portions 33 so that fluid is supplied continuously to both channels. The same is true of the exhaust channels, 28, 32, which are connected by the registering ports 27 and 31.

The pump is reversible, that is to say, may be driven in either direction with the same efficiency, and when reversed the direction of flow of fluid through the pump is reversed so that the inlet and outlet 13, 14 become respectively the outlet and inlet. Either of the rotors may be the driver, the other one being driven therefrom by the plunger element 24.

It will be noted that the entire pump comprises but five parts, to wit, the two casing sections, the two rotors, and the plunger element. These parts are so shaped and constructed that expensive machine operations are unnecessary so that the pump may be very cheaply made. It is also very durable, efficient in operation, and may easily be lubricated.

If the channels and ports 29, 30, 31, 32 in the casing-section 10^b be eliminated, the pump will function as a single plunger pump, in which case the size of the parts in the casing section 10^b may be greatly reduced, that is to say, the casing section may be thin in an axial direction, the rotor 18 may likewise be thinner and smaller in diameter, and the plunger slide 24^b may be of much smaller dimensions to form merely a rectangular projection on the slide 24^a cooperating with the slot in the rotor 18 to effect the reciprocation of the slide 24^a in its rotor 17.

We claim as our invention:

1. A rotary pump comprising, in combination, a casing having two cylindrical bores eccentric to each other, two rotors in

- said bores abutting face to face and turning on axes eccentric to each other, said rotors having diametrical slots in their adjacent faces extending perpendicularly to each other, a unitary plunger comprising two slides disposed perpendicularly to each other and fitting respectively in said slots whereby a relative reciprocation of each slide in its slot will be caused during rotation of said rotors, and suitable inlet and outlet passages in said casing arranged to communicate with said slots.
2. A rotary pump having, in combination, a casing having a cylindrical bore, a rotor fitting concentrically in said bore and having a diametrical slot in one side face, a slide fitting in said slot and being shorter in length than the diameter of said rotor, the casing having an inlet and an outlet each including a channel extending circumferentially around and opening into said bore, the two channels being located at diametrically opposite sides of said bore, the adjacent ends of the inlet and outlet channels being spaced apart a distance equal to the width of said slot and the slide therein, a non-circular part fixed to said slide, and a rotary element mounted in the side of said casing which opposes the slotted side of said rotor, said element rotating on an axis eccentric to the axis of said rotor, said element having an elongated diametrical slot therein disposed perpendicularly to the slot in the rotor and fitting said non-circular part to prevent relative rotary movement of said part and element but permit relative sliding movement of said part in the slot in said element, whereby the rotation of said rotor will cause relative reciprocation of said slide in its slot in the rotor to cause fluid to be drawn from said inlet channel into one end of said slot in the rotor continuously for approximately one-half revolution of the rotor and to cause simultaneously fluid to be discharged from the opposite end of the slot in the rotor into the outlet channel during such one-half revolution.
3. In a rotary pump, in combination, two rotary eccentric parts having two diametrical slots in their respective adjacent faces disposed perpendicular to each other and an element connecting said rotary parts to drive one from the other, said element having two portions fitting slidably but non-rotatably in said slots.
4. A compound plunger for rotary pumps comprising two plunger elements each having flat parallel opposed sides, said elements being disposed perpendicular to each other and being formed out of an integral piece of metal.
5. In a rotary pump, in combination, two rotary eccentric parts having two diametrical slots in their respective adjacent faces disposed angularly to each other, and an element connecting said rotary parts to drive one from the other, said element having two portions fitting slidably but non-rotatably in said slots.
6. A compound plunger for rotary pumps comprising two plunger elements, each having flat parallel opposed sides, said elements being disposed angularly to each other and being formed out of an integral piece of material.
7. A compound plunger for rotary pumps comprising two plunger elements, each having flat parallel opposed sides, said elements being disposed angularly to each other and being rigidly connected together with said flat sides adjacent each other.

In testimony whereof we have hereunto affixed our signatures.

WILLIAM H. PASCOE.
JOHN TATTER.
